United States Patent Office

Des. 183,646
Patented Oct. 7, 1958

183,646

HANDKERCHIEF

Hugh P. Cash, Washington, D. C.

Application April 3, 1958, Serial No. 50,319

Term of patent 7 years

(Cl. D3—12)

Fig. 1 is a plan view of a handkerchief showing my new design and

Fig. 2 is an enlarged fragmentary view showing one of the corners in detail.

I claim:

The ornamental design for a handkerchief, as shown.
